UNITED STATES PATENT OFFICE.

HAROLD A. EVANS, OF LYNN, AND GEORGE W. JACQUES, OF NEW BEDFORD, MASSACHUSETTS, ASSIGNORS TO ATLAS TACK CORPORATION, OF FAIRHAVEN, MASSACHUSETTS, A CORPORATION OF NEW YORK.

TAPE-APPLYING FASTENER-SETTING MACHINE.

Application filed April 9, 1924. Serial No. 705,239.

This invention relates to machines for setting fasteners, more particularly what may be termed "barrel" fasteners, having tubular or cylindrical portions which extend 5 through the work and which are headed over on opposite sides, such for example as lacing hooks, being concerned more particularly with means by which a reinforcing tape may be fed with the work so that the fasteners 10 when set fix the tape to the work. In accordance with this invention provision is made by which when the desired number of fastenings have been set the length of tape through which they pass may be readily detached 15 from the remainder thereof. In order that the length of tape may conform to work in which a series of fasteners are set in other than a straight line, and without the necessity of slitting the tape between 20 successive fasteners, this invention contemplates the use of bias tape. By using a bias tape as a stay for the work the fasteners may be set simultaneously in the work and the stay, while the stay is being conformed 25 in an uninterrupted flat length to the fastener line by distortion of the tape in its own plane. By cutting such tape partly across at the proper intervals sections fixed to the work by the series of fasteners may 30 be readily detached from the remainder of the strip by merely pulling therefrom. Provision is therefore made in the invention by which at the completion of the setting of each series of fasteners the tape is slit to 35 define a transversely weakened break line for a succeeding length of tape to be fixed by the setting of a succeeding series or row of fasteners, the distance between successive slits being adjustable to provide for different 40 spacing and number of fasteners in each row.

For a more complete understanding of this invention reference may be had to the accompanying drawings in which

45 Figure 1 is a fragmentary front elevation of a lacing hook setting machine showing the tape guiding and slitting mechanism in position thereon.

50 Figure 2 is a perspective showing this mechanism and its actuator, the presser foot being omitted.

Figure 3 is a perspective partly broken away and parts separated of the same mechanism.

Figure 4 is a fragmentary side elevation 55 of the machine showing the treadle control.

Figure 5 is a side elevation of the tape handling mechanism.

Figure 6 is a rear elevation of the same.

Figure 7 is a section on line 7—7 of Figure 5.

Figure 8 is a fragmentary view of the shoe upper showing the tape and hooks applied, the facing strip being partly detached.

Figure 9 shows in plan a piece of bias 65 tape showing the manner in which it is slit and a section fixed to work detached therefrom.

Referring to Figures 1 and 4, at 1 is indicated a machine pedestal which as shown 70 is supported on a bench or table 2, this pedestal having a forwardly extending bracket 3 thereon to which is fixed a work table 4. Cooperating with the upper face of the work table (Figure 1) is a presser foot 5 fixed to 75 a presser foot lifter rod 6 guided for vertical movement through an opening in the bracket 3, the presser foot normally being urged downwardly against work on the work table 4 by means of a compression spring 7 80 surrounding the lifter rod 6 and bearing at its upper end against the bracket 3 and engaging the collar 7^a fixed to the rod 6 at its lower end. At 8 is indicated a punch and set holder carried by a slide 9 movable so 85 that the punch may form a hole in the work supported on the work table 4 when substantially in the dotted line position shown in Figure 1, and then carry the work into the full line position shown in Figure 1 in 90 alignment with a hook-presenting and setting mechanism indicated generally at 10. This mechanism is of any usual construction and is well known in the art so that further detail showing is unnecessary. 95

At 15 (Figures 1, 2, 5 and 6) is shown a support carried by the machine frame, this support having a T slot 16 cut in its lower face as shown best in Figures 2 and 6. Within this T slot is slidably a correspondingly shaped member 17 carried at the upper end of a block 18. This block 18 is cut away above its lower end to form a pair of posts 19 defining a guideway therebetween in which is slidably guided for vertical 100 movement the portion 20 of a knife carrier 21. On one side of this knife carrier is a thin bladed knife 22 which projects do 105

wardly past the corresponding face of the block 18, this knife being fixed to the carrier as by means of a screw 23. On the other side of the carrier 21 is fixed a clamping plate 24 for a purpose which will later appear. The lower face of the block 18 is provided with a slot 25 through which a tape 26 may be passed to be presented superposed on the work to the fastener setting mechanism. A cover plate 27 fixed to the lower face of the block 18 acts to hold the tape in position in the slot. A plate 28 having a slot 29 in one face through which the knife 22 may pass and a slot 30 through which the tape may be threaded is made fast to the face 31 of the block as by means of screws 32. The knife is thus enclosed, the block and plate acting as a die and supporting the tape on both sides adjacent to the cutting line. The carrier 21 is normally held in elevated position by means of a spring 35 reacting between the lower face of the portion 20 of the carrier and the upper face of the block 18 between the posts 19. Above the carrier 21 is pivoted on the screw 40 a lever 41, one end of which engages the upper face of the block 21 and the other end 42 of which extends laterally from the block 18 in position to be contacted by the outer end of a plate 44 carried at the upper end of the presser foot lifter rod 6. By raising this presser foot lifter the lever 41 is rocked to depress the carrier 21, causing the knife 22 to be projected downwardly and cut a slit through the tape, the knife being narrower than the slot 25 and positioned centrally thereof so that an uncut margin, as shown at 50 in Figure 9, is left at the ends of each slot 51 formed by the knife. When the knife 22 is in projected position, having effected the slitting of the tape, the plate 24 clamps the tape against the upper edge of the cover plate 27 for a purpose which will later appear.

The block 18 for the slitting and clamping mechanism is adjustable along the support 15 and in order to hold it in adjusted position a locking finger 55 may be fixed to one face thereof as by means of a screw 56, this finger engaging over the upper face of the support 15 and having a V shaped projection 57 on its lower face engageable selectively in any of a plurality of notches 58 in the upper face of the support 15.

The presser foot lifter may be actuated in time with the starting and stopping of the machine. For this purpose a lever 60 pivoted at 61 to the machine frame has one arm 62 engageable with the lower end of the presser foot lifter rod 6. To the other end of this arm 63 is attached a chain 64 fastened to the heel end of a foot treadle 65 (see Figure 4). To the toe end of this treadle is fixed a chain 66, the upper end of which is

attached to a controller rod 67 for the starting and stopping mechanism. This mechanism may be of any suitable construction, but as hereinbefore shown is of the well known pin type in which the upper end of the controlling rod 67 has an abutment member 68 which may be raised into the path of motion of a stop lug 69 of the clutch or depressed out of contact therewith. When the abutment 68 is out of the path of the lug, 75 the clutch is connected for operation of the machine, but when the abutment 68 is allowed to raise, as soon as the clutch lug 69 contacts therewith, its rotation is stopped thereby and the clutch is disconnected. 80

A tape, preferably a bias tape, is threaded through the slots 30 and 25 of the guide block 18 while the knife and clamp carrier is in retracted position and the end of the tape is brought through a slot in a guide 85 movable with the punch carrier over the work table to an extent sufficient to be engaged and punched when the machine is started.

The presser foot is then raised by depressing the heel of the treadle to permit work to be inserted thereunder, thus causing the carrier to descend and cut a slit through the tape and to clamp the tape between this slit and the fastener setting mechanism. 90 The toe of the treadle is then depressed, permitting the presser foot to clamp the work in position and permitting the spring 35 to retract the knife and clamping plate from the tape. Sufficient depression of the toe of the treadle acts to start the machine, whereupon the punching device is moved from its last setting position over the end of the tape which is punched thereby as the punch descends to form a hole in the work. The 100 punch then moves by engagement with the tape and the work, feeding both together to the setting position where a hook is presented to the hole and set through both the work and the tape. The punch then raises 105 and retracts and forms a succeeding hole through both the tape and the work in which the next hook is set in like manner, this continuing until the desired number of hooks 110 in the series having been set through both the tape and the work. The tape being a bias tape permits the fasteners to be set in other than a straight line, the tape being conformed in continuous flat condition to the configuration thereof as fed without requiring any slitting of the tape between the successive fasteners, this being shown clearly in Figure 8.

When the desired number of fasteners has been set the operator depresses the heel end 115 of the treadle causing the machine to stop and the presser foot to be raised to release the work. This causes the knife and clamping plate to be brought down, the knife acting to slit the tape at a distance spaced 120

from the slit first cut sufficient to define a section of tape of a length suitable for setting the desired number of fasteners in a succeeding series, the slitting and clamping mechanism being adjustable along the support 15 to provide for different numbers of fasteners to be set and variations in the spacing thereof.

After the presser foot has been raised the work may be removed from the machine and by a quick pull thereon the tape section fixed to the work by the series of fasteners set therein may be detached from the remainder of the strip of tape at the slit first made by the knife which is now between the clamping mechanism and the setting mechanism and leaving the forward end of the succeeding length projecting through the guide 33 in position to be engaged and punched on a succeeding actuation of the machine. The clamping plate 24 bearing on the tape between the knife and the setting mechanism prevents the break from occurring at the knife. This is clearly shown in Figure 9, the tape section attached to the work W parting from the remainder of the tape strip at *a*, while being clamped at the line *b* and newly slit at *c*.

Where bias tape is employed not only is it possible to conform the tape to the configuration of the line of fasteners, but it also renders easy the detachment of a section made fast to the work at the slit, it only being necessary to separate the oppositely extending short diagonal threads at the narrow uncut margins 50 as shown more clearly in Figure 9, it being unnecessary to break any threads in this operation.

A succeeding piece of work may then be placed beneath the presser foot in position for the punch to punch the tape and the work and then feed the two to setting position to successively set the desired series of fasteners therein whereupon on stopping the machine and raising the presser foot as just described the next section of tape attached to the work may be detached at the adjacent slit 51, a slit defining the rear end of the succeeding section being made when the presser foot is raised.

Having thus described an embodiment of this invention it should be evident to those skilled in the art that various changes and modifications may be made therein without departing from its spirit or scope as defined by the appended claims.

We claim:

1. The method of reinforcing work in which a row of barrel fasteners are set in a curved line, which comprises progressively feeding the work and a bias stay tape to a fastener setting mechanism, and simultaneously setting such fasteners in the work and the tape while conforming the tape in an un-

interrupted flat length to the fastener line 65 by the distortion of the tape in its plane.

2. The method of reinforcing work in which a curved row of fasteners are to be set which comprises defining by a weakened portion a section of bias tape of sufficient 70 length to reinforce the row, setting the fasteners of the row through the tape section and work while conforming the tape section to the configuration of the row, and then detaching the tape section at the weakened 75 portion from the remainder of the strip.

3. In combination with a fastener setting machine having barrel fastener setting mechanism, of a support, a tape guide adjustable on said support toward and from said mechanism, a knife carried by said guide, and means for actuating said knife to cut a tape extending through said guide.

4. In combination with a fastener setting machine having barrel fastener setting mechanism, of a support, a tape guide adjustable on said support toward and from said mechanism, a knife carried by said guide, and means for actuating said knife to partly sever a tape extending through said guide.

5. In combination with a fastener setting machine having barrel fastener setting mechanism, of a support, a guide block adjustable on said support toward and from said mechanism, said guide block having a slideway and a slot to guide a tape to said mechanism, a carrier movable in said slideway, a knife on said carrier projectable to cut a slit through a tape in said slot on sliding of said carrier in one direction, and a clamping member on said carrier acting to clamp the tape within its slot between said knife and mechanism when said carrier is in knife-projected position.

6. In a fastener setting machine, barrel fastener setting mechanism, means for leading a tape to said mechanism, and means for laterally weakening the tape to define the lines of breakage between tape sections to be fixed to work by a row of barrel fastenings set by said mechanism.

7. In a fastener setting machine, fastener setting mechanism for setting a row of fasteners, means for leading a tape to said mechanism, and means actuatable by the operator after a setting operation to weaken the tape to define the rear end of a tape section to be fixed to work by a subsequently set row.

8. In a fastener setting machine, barrel fastener setting mechanism, means for leading a tape to said mechanism to permit continuous sections thereof to be fixed to work by a row of barrel fasteners set by said mechanism, and means for weakening the tape to define lines of breakage between said tape sections.

9. In a fastener setting machine, barrel fastener setting mechanism, means for lead-

ing a tape to said mechanism to permit sections thereof to be fixed to work by fasteners set by said mechanism, and means for weakening the tape by slits extending transversely between unsevered side margins to define lines of breakage between said tape sections.

10. In a fastener setting machine, fastener setting mechanism, means for leading a tape to said mechanism, means for clamping work to which sections of the tape are to be attached by fastenings set by said mechanism, and means actuatable on the release of said clamping means to remove the work to define by a weakened portion a section of said tape.

11. In a fastener setting machine, fastener setting mechanism, means for leading a tape to said mechanism, means for clamping work to which sections of the tape are to be attached by fastenings set by said mechanism, and means actuatable on the release of said clamping means to remove the work to transversely weaken said tape to define a section thereof in advance of the section fixed to the work.

12. In a fastener setting machine, fastener setting mechanism, means for leading a tape to said mechanism, means for clamping work to which sections of the tape are to be attached by fastenings set by said mechanism, means actuatable on the release of said clamping means to remove the work to weaken the tape on a line defining a section of said tape, and means to clamp the tape between the weakened lines and said mechanism, whereby on removing the work by said machine the tape may be broken at a previously formed line at the rear end of the fixed section.

13. In a fastener setting machine, a work table, a presser foot for holding work on said table, mechanism for setting fasteners in the work on said table, a guide member for leading a tape to the work for sections thereof to be fixed to the work by fasteners set by said mechanism, means for stopping the machine and raising the presser foot to release the work at the completion of a setting operation, and means acting on the raising of the presser foot for transversely weakening the tape to define a parting line between successive tape sections.

14. In a fastener setting machine, a work table, a presser foot for holding work on said table, mechanism for setting fasteners in the work on said table, a guide member for leading a tape to the work for sections thereof to be fixed to the work by fasteners set by said mechanism, means for stopping the machine and raising the presser foot to release the work at the completion of a setting operation, means acting on the raising of the presser foot for transversely weakening the tape to define a line of break-

age between successive tape sections in advance of the section attached to the work, and means acting to clamp the tape adjacent to such weakening and between such weakening and said mechanism to insure breakage of the tape at the previously formed weakened portion defining the rear end of the section attached to the work.

15. In a fastener setting machine, a work table, a presser foot for clamping work on said table, a presser foot lifter, fastener setting mechanism for setting fasteners in work on said table, a support, a block adjustable on said support toward and from said mechanism and having a guide slot for leading a tape toward said mechanism to cause sections thereof to be fixed to the work by fasteners set by said mechanism, a carrier slidable vertically on said block, a lever pivoted to said block and having one arm engageable with the upper face of said carrier, a knife on said carrier actuatable on depressing of said carrier to cut a slit transversely of said tape to define a breakage line between successive tape sections, means normally urging said carrier upwardly to knife-retracted position, and a plate on said presser foot lifter engageable with the other end of said lever as said presser foot is raised to release the work to depress said carrier and slit the tape.

16. In a fastener setting machine, a work table, a presser foot for clamping work on said table, a presser foot lifter, fastener setting mechanism for setting fasteners in work on said table, a support, a block adjustable on said support toward and from said mechanism and having a guide slot for leading a tape toward said mechanism to cause sections thereof to be fixed to the work by fasteners set by said mechanism, a carrier slidable vertically on said block, a lever pivoted to said block and having one arm engageable with the upper face of said carrier, a knife on said carrier on one face of said block actuatable on depressing of said carrier to cut a slit transversely of said tape to define a breakage line between successive sections, a clamping plate on said carrier on the opposite face of said block to clamp the tape between said knife and mechanism when said carrier is in depressed position, means normally urging said carrier upwardly to knife and clamp-retracted position, and a plate on said presser foot lifter engageable with the other end of said lever as said presser foot is raised to release the work to depress said carrier and slit and clamp the tape, said clamp acting on removal of the work to insure the breaking of the tape along a previously formed slit defining the rear end of the tape section fixed to the work.

17. The method of reinforcing work in which a row of fasteners is to be set, which comprises defining by a weakened portion

a section of bias tape of sufficient length to reinforce the row, setting the fasteners of the row through the tape section and work while conforming the tape section to the configuration of the row, defining a next section by a weakened portion, holding said next section, and detaching the first tape section therefrom while said next section is being held.

16. 18. In a fastener setting machine, barrel

fastener setting mechanism, a guide for guiding a tape to said barrel fastener setting mechanism, and means actuatable to cut a tape in said guide by a single transverse slit terminating inwardly of both side edges. 15

In testimony whereof we have affixed our signatures.

HAROLD A. EVANS.
GEORGE W. JACQUES.
